US00D911441S

(12) **United States Design Patent** (10) Patent No.: **US D911,441 S**
(45) Date of Patent: **** Feb. 23, 2021**

(54) **WHITEBOARD**

(71) Applicant: **BI-SILQUE, S.A.**, Esmoriz (PT)

(72) Inventor: **Adriano Alexandre Oliveira Pereira**,
Esmoriz (PT)

(**) Term: **15 Years**

(21) Appl. No.: **35/507,933**

(22) Filed: **May 24, 2019**

(80) **Hague Agreement Data**

Int. Filing Date: **May 24, 2019**

Int. Reg. No.: **DM/203857**

Int. Reg. Date: **May 24, 2019**

Int. Reg. Pub. Date: **Nov. 29, 2019**

(51) **LOC (13) Cl.** **19-06**

(52) **U.S. Cl.**

USPC **D19/113**

(58) **Field of Classification Search**

USPC D19/26-33, 81, 88, 113, 114; D6/310,
D6/311; D7/698; D20/10, 19, 39, 40,
D20/41, 42
